United States Patent Office.

JOHN H. HERITAGE, OF WILMINGTON, DELAWARE.

Letters Patent No. 99,316, dated February 1, 1870.

CULINARY STEAMER.

The Schedule referred to in these Letters Patent and making part of the same.

I, JOHN H. HERITAGE, of the city of Wilmington, in the State of Delaware, have invented certain Improvements in Steam-Colanders, of which the following is a specification.

Nature and Objects of the Invention.

My invention consists in employing colanders, of varying size, and certain pans or longitudinal receptacles, located in a close box, and designed for the reception of articles of food to be cooked by the direct action of steam in the former, and by the indirect action thereof in the latter, or by the heat emanating from the steam, which cooks the food in the colanders.

Description of the Accompanying Drawings.

Figure 1 is a plan view, with the colanders removed, and the upper lid thrown back, and the lower lid raised.

Figure 2 is a longitudinal view, with one side broken away, to show the stands and colanders.

A is a box or receptacle, which is made, preferably, of quadrilateral shape, and provided with the lid a, and auxiliary cover or heater a', which latter is hinged to the top of the main lid aforesaid, and closes tightly thereon, the pivotal piece or catch f, in connection with the metallic arch g, being employed to secure it closely thereto.

The flange h on the box, and the flange i on the lid thereof, may be made of wire, encircled by metal, or in any ordinary way, to make a closely-fitting lid, to prevent the escape of steam.

P is a catch, for securing in position the lower lid.

The box aforesaid has located therein, at the lower part thereof, a pipe, K, provided with a stop-cock, and one also at the upper part thereof, L, which is also provided with a stop-cock or valve. The pipe K, at the lower part of the box, is designed to admit the outflow of the water or condensed steam collecting therein, and the pipe L, located near the top of the box, is designed to admit the escape of steam, when desirable.

B is a longitudinal steam-pipe, located immediately beneath a series of colanders, the steam being supplied to the longitudinal pipe by the transverse or supply-pipe M, which latter connects with or is attached to the former at a point equidistant from the two ends thereof.

The supply-pipe M is provided with a valve or stop-cock, wherewith to regulate the admission of steam, and the longitudinal pipe B is provided with a series of valves or stop-cocks, represented by W, located in small pipes connecting therewith, and projecting vertically therefrom, and immediately beneath a series of colanders, which are designed for the reception of the article or articles to be cooked.

C C C C are stands, which are rigidly attached to the bottom of the box. They are similar in construction, but, preferably, of varying size. They have, located in the four corners, and near the top thereof, horizontal metallic projections T, forming a platform for each colander, just above the steam stop-cocks or valves aforesaid.

D D D D represent a series of colanders, adapted, by size, to fit the stands aforesaid. They are provided with handles, and may have closely-fitting and fastening lids, when it is desirable to economize the quantity of steam employed.

F is a perforated dish-shape receptacle or pan, provided with handles, by which it is lowered and placed upon the flange e, formed in the corners of the box.

A series of colanders may also be arranged in a proper receptacle, located vertically or in tiers, one above another, and the steam, ascending through the lower colanders, may be the only means employed in the upper tier or tiers for cooking therein, or the main steam-pipe may be connected with a conduit, conveying the steam immediately beneath the upper tiers, as may be preferable in practice.

Claims.

1. The combination of the colanders D, the pan F, auxiliary heater a', and box A, as herein described, and for the purpose specified.
2. The stands C, longitudinal steam-pipe B, supply-pipe M, escape-pipe L, waste-pipe K, and catch f, constructed, arranged, and operating substantially as herein shown and described, and for the purpose set forth.

JOHN H. HERITAGE.
